PAVEMENT SLAB CONNECTOR

Franklin W. Abel, Franklin, Ind.

Application May 10, 1946, Serial No. 668,925

2 Claims. (Cl. 94—8)

1

This invention relates to means for forming pavements, including both roadways and sidewalks, and the like. The invention embodies the forming of a roadway with a plurality of individual, pre-cast slabs of concrete, and providing very simple inter-connecting means between slabs whereby the slabs are held to have their upper faces at common elevations so that there may be no difference in elevation encountered in going from one slab to the other. That is to say, even when the roadway is inclined as on a hill, the adjacent edge positions of the slabs will be so positioned as to have no "bump" in going across from one to the other. A preliminary object of the invention resides in the slab inter-connecting means, comprising an extremely simple mechanism not only cheap in cost of production, but simply and easily manipulated on the job as the slabs are laid.

These and many other objects and advantages of the invention will appeal to those versed in the art in the following description of one particular form of the invention, as illustrated in the accompanying drawings, in which

Fig. 1 is a top plan view of a fragment of a roadway embodying the invention;

Fig. 2, a vertical section in the line 2—2 in Fig. 1;

Fig. 3, a vertical section on the line 3—3 in Fig. 1; and

Fig. 4, a detail on an enlarged scale of the slab inter-connecting means with a portion of the cover removed.

Like characters of reference indicate like parts throughout the several views in the drawings.

Individual slabs 10, 11, 12 and 13, all of the same general conformation, are pre-cast at some central location convenient for the work and for delivery of the necessary materials. In each slab there is moulded a pocket 14 entering from a vertical face. The number of these pockets 14 may vary in accordance with the sizes of the slabs employed. For example, in a roadway the slabs may be of sufficient size to extend entirely across the roadway, or halfway across, or a lesser proportion, all as may be desired. In the larger slabs there will be a larger number of the pockets 14 along the vertical faces of the slabs. Within the pocket 14 in each instance there projects a bar 15, herein shown as a round bar with one end anchored within the slab 10. Then, in the next adjacent slab 11 there is a like bar 16 anchored therein to extend from the vertical face 17 into the pocket 14 of the slab 10. By suitable leveling of the undergrade 18, these bars 15 and 16 are

axially aligned, the bars being properly located from the side edges of the respective slabs to permit lateral alignment. When the two bars 15 and 16 are vertically aligned the top faces of the slabs 10 and 11 are properly aligned to be in the same continuous plan.

Now in order to maintain the top faces of the two slabs 10 and 11 in that alignment, I provide a thick-walled tubular sleeve 19 which will slide over these bars 15 and 16. Initially assuming that the slab 10 is first laid down, the sleeve 19 may be pushed back on the bar 15 to be entirely confined within that length of the bar 15 which extends from the vertical face of the slab 10. This permits the bar 16 to be aligned with the bar 15 without interference by the sleeve 19, then when the two bars 15 and 16 are aligned, the sleeve 19 may be slid along the bar 15 to telescope over the end of the bar 16 and to remain telescopically in part over the end of the bar 15.

The sleeve 19 is preferably fixed in this position where it extends by equal lengths over the ends of the bars 15 and 16. Any suitable means may be employed to so fix the sleeve 19 in position, the simple means being herein shown such as a pin 20 inserted in a hole in the bar 15 and a pin 21 inserted in a hole in the bar 16, the pins 20 and 21 being spaced from the ends of their respective bars those distances which will retain the sleeve 19 therebetween without substantial movement along the bars. Preferably the sleeve 19 is lined with a resilient tube 22 such as fibre to permit a controlled yielding movement vertically of one slab relative to the other without any appreciable changing of the elevation of one slab in respect to the other.

The pocket 14 must of course be closed over to provide a smooth continuous road or walk surface thereacross. One such closure means is illustrated in the accompanying drawings as consisting of a cover 23 made of concrete and resting on a shoulder 24 formed around the upper margin of the pocket 14 and across an upper edge portion of the adjacent slab 11. This cover 23 is retained in fixed position by means of a plurality of sleeve screws 25, herein shown as two in number. Each of these sleeve screws 25 screw-threadedly engage with a stud 26 held in fixed position by a plate 27 projecting into the pocket 14 and anchored by ends in the slab 13. In the present showing the stud 26 in each instance passes through a hole in a plate 27 to have upper and lower nuts 28 and 29 screw-threadedly engage the stud and fix it to the plate 27 by clamping the plate therebetween.

The cover 23 is provided with a resilient packing 30, both between its underside and the shoulder 24 and also extending around the vertical edge portion of the cover. Also, the undersides of the heads of the screws 25 have a resilient packing gasket 31 thereunder. As is the usual practice, each slab is separated from the other by their opposing vertical faces by an expansion and contraction packing 32.

Therefore, it is to be seen that by means of the simple construction described the slabs 10 and 13, and for that matter the lateral slabs 10 and 11, and so on, may expand and contract under temperature changes without destroying the inter-leveling means and without leaving any appreciable gaps therebetween, even around the pocket covers 23. The pockets 14 under the covers 23 may be filled, preferably with oiled sand 33, in order to prevent rusting of the various parts one to the other, although the use of the fibre sleeve 22 between the sleeve 19 and the bars 15 and 16 will prevent bonding by rusting.

While I have herein shown and described the invention in the one particular form, it is obvious that mechanical variations may be employed without departing from the spirit of the invention, and therefore I do not intend to be limited to that precise form beyond the limitations as may be required by the following claims.

I claim:

1. In a pavement formed by a plurality of pre-cast units, one of the units at least having a cavity entering from an edge, a bar anchored in said one unit to extend by a length into said cavity; a second bar anchored in an adjacent unit to extend therefrom and align axially with said first bar when the top, adjacent edge portion of the two units are at a common elevation; a rigid sleeve telescoping over said two bars; a resilient sleeve closely fitting within said rigid sleeve; and means retaining the sleeves in position bridging across both of said bars; said retaining means comprising an abutment carried by each of said bars; said sleeve having a

length not to exceed the length exposed within said cavity of the longest of said bars, plus the axial distance therebetween.

2. In a pavement formed of removable and replaceable precast slabs, one of the slabs at least having a cavity therein entering from a vertical edge; a bar anchored in said one slab to extend a distance horizontally into said cavity short of said vertical edge; a second bar anchored in an adjacent slab positioned to enter substantially into said cavity in substantially horizontal alignment with said first rod; a rigid sleeve telescoping said first bar and being less than the length thereof exposed within said cavity; a resilient sleeve telescoping within said rigid sleeve, whereby said combined sleeves may be shifted to telescopically interconnect said first and second bars; an oil-sand filling within said cavity completely covering over said rods and said sleeves; a shoulder around the upper marginal portion of said cavity; a rigid cap supported by said shoulder; a resilient packing between said cap and said shoulder; said oil-sand filling extending against the under side of said cap; and means releasably securing the cap against said packing and said sand.

FRANKLIN W. ABEL.
